(57) **CLAIM**

The ornamental design for a disc golf disc holder, as shown and described.

DESCRIPTION

FIG. 1 is a perspective view of the disc golf disc holder; FIG. 2 is a front view of the disc golf disc holder; FIG. 3 is a rear view of the disc golf disc holder; FIG. 4 is a right side view of the disc golf disc holder; FIG. 5 is a left side view of the disc golf disc holder; FIG. 6 is a top view of the disc golf disc holder; and, FIG. 7 is a bottom view of the disc golf disc holder.

The portions of the disc golf disc holder shown in broken lines form no part of the claimed design.

Dash-dash broken lines shown in the drawings illustrate portions that form no part of the claimed design.

Dash-dot broken lines shown in the drawings illustrate boundaries that form no part of the claimed design.

Dash-dot break lines that separate portions of the disc golf disc holder, and a space and a bracket between the break lines, form no part of the claimed design.

The terms top, left, right, bottom, rear, side, and front are used for reference only and do not limit the claimed design. Shading lines shown in the drawings represent surface contours, or transparency, translucency, or opacity, and not surface ornamentation, and such lines, in and of themselves, are not part of the claimed design.

Portions of the disc golf disc holder not shown in the drawings form no part of the claimed design.
